UNITED STATES PATENT OFFICE.

HARRY A. KUHN, OF PITTSBURGH, PENNSYLVANIA.

METHOD OF MINING COAL.

1,194,298.

Specification of Letters Patent.

Patented Aug. 8, 1916.

Application filed October 21, 1913. Serial No. 796,497.

To all whom it may concern:

Be it known that I, HARRY A. KUHN, a citizen of the United States, and resident of Pittsburgh, in the county of Allegheny and State of Pennsylvania, have invented a new and useful Improvement in Methods of Mining Coal; and I do hereby declare the following to be a full, clear, and exact description thereof.

10 My invention relates to a method of mining coal.

The object of my invention is to provide a method of mining coal by means of which the coal, after it has been undercut and shot, 15 may be readily and quickly removed without involving the risk of loss of life, and at the same time dispensing with the digging of the coal by means of picks, as in the method now commonly employed.

20 To these ends my invention consists, generally stated, in making a cut or undercut in the solid wall of coal and expanding the coal along its lines of cleavage, substantially filling the space thus provided by the cut or undercut, the coal settling down where an undercut is made on the floor formed by the undercut, or swelling into the cut wherever made, finally under-mining the coal along the line of the original cut, and 25 at the same time conveying it to the point of loading.

In the accompanying drawings I have illustrated apparatus for carrying out my improved method in which—

30 Figure 1 is a plan view showing the primary cutting or undercutting unit making the original cut or undercut in the coal; and the secondary cutting, digging and conveying unit in the rear thereof; Fig. 2 is a plan view showing the primary cutting or undercutting unit in normal position on the digging and conveying frame, and the latter advanced to remove the coal; Fig. 3 is a side elevation of the whole digging and conveying machine in operation, the coal having been shot and settled into the original undercut; Fig. 4 is a face view of the wall of coal after it has been undercut and before shooting; Fig. 5 is a like view showing the 40 coal after it has been shot and expanded along its cleavage line, ready to be removed; Fig. 6 is an enlarged plan view of the digging and conveying unit; Fig. 7 is a longitudinal section of same; Fig. 8 is a section 45 on the conveyer flight; and Figs. 9 and 10 are other forms of same.

While I have illustrated one form of apparatus for carrying out my improved method, this apparatus forming the subject matter of a separate application filed May 18, 1914, Serial No. 839,325, I may employ other forms of apparatus for carrying out my improved method.

The numeral 2 designates a suitable frame which may be composed of suitable parts, 50 uniting to form a rigid construction. This frame is supported in an inclined position, its rear end being carried by the truck 3, which is provided with the axle 4 on which the traction wheels 5 are mounted. The 55 wheels 5 and the mechanism for driving same are housed in the box or casing 6. Within the casing 6 on the axle 4 is the friction sheave 7, which is engaged by the friction sheave 8 on the shaft 9. This shaft 9 is suspended from the bars 10, which are pivoted to the bracket 11. A toggle member 12 is connected to the shaft 9, and said toggle is pivoted at 13 to the link 14, which is pivoted to the lug 15 on the casing 6. The 60 other end of the toggle is connected to the crank arm 16 on the stud shaft 17, which is mounted on the bracket 18. To the outer end of the stud shaft 17 is connected the operating lever 19. It is apparent that by 65 operating the lever 19 the toggle member 12 is operated to move the friction member 8 into or out of contact with the friction sheave 7 to transmit power to the driving 70 axles, as fully hereinafter set forth.

75 Mounted on the shaft 9 is a sprocket wheel 20, the chain 21 passing around the sprocket wheel 20 and around the sprocket wheel 22 of the shaft 23, mounted in the frame. Mounted on the shaft 23 is the 80 worm wheel 24 which is connected with the worm 25 on the shaft 26. This shaft 26 has the gear wheel 27, which is engaged by the pinion 28 on the counter shaft 29. The gear wheel 30 on the shaft 29 is engaged by the 85 driving pinion 31 on the shaft 32. The shaft 32 has the clutch box 33, adapted to receive the square end of shaft 34 of the motor 35. This motor, which in the present case is an electric motor, is the driving 90 power for the primary cutting unit 36, which may be of the ordinary construction, comprising the chain cutter 37 passing around the sprocket wheel 38 at the forward 95 and rear ends of the mining machine frame, 100 said cutter chain being driven by power transmitted from the motor 35 to the driv-

ing sprocket wheel. When this primary cutting unit is mounted on the frame 2, of the digging and conveying apparatus, the motor shaft 34 engages the clutch box 33, and power is transmitted from the motor to the mechanism for connecting the traction wheels 5 and the other parts of the mechanism to be hereafter described. The primary cutting unit is provided with feed and tail ropes in the ordinary manner, and by means of said ropes and the customary jacks or anchors this mechanism drags itself off the frame 2 and back thereon, as well as into and across the cut when in position for undercutting.

The numeral 39 indicates the rope drum around which the feed rope 40 passes and the numeral 41 designates the drum around which the tail rope passes. Customary pulleys 42, 43, 44 and 45, for the guiding of the feed and tail ropes are provided. The frame 2 of the digging and conveying apparatus is provided with the hook 46, to which the feed rope 40 is connected when the primary cutting unit is to be dragged up on the frame 2, as indicated in Fig. 3. The primary cutting unit when up in this position, with its motor shaft 34 in engagement with the clutch box 33, forms a power plant for operating the digging and conveying apparatus. The primary cutting unit and the secondary cutting, digging and conveying unit form one complete machine for mining coal.

The forward end of the frame 2 is supported by the roller 47, which is fitted to turn in the manner of a caster, and a rope 48 is connected to each side of the bar 49, said rope passing back and around the drum 50. This drum may be operated by the crank 51, and by turning this crank in one direction the roller 47 will be turned to guide the machine one way, and by reversing the direction of the movement of the crank the roller turns to direct the machine in the other direction.

At the rear end of the frame 2 is the sprocket wheel 52, and at the forward end of said frame are the sprocket wheels 53. The chain 54 passes around said sprocket wheels and said chain carries the flights 55 at intervals. The outer ends of the flights 55 are formed with cutters or diggers, 55', which are adapted to cut or dig under the body of coal which has been lowered by shooting, as fully hereinafter set forth. As shown in Fig. 8 the cutters are secured to the flights by means of nuts and bolts which project upwardly and aid in dislodging the coal. Furthermore the front edges of the flights are beveled to enable them to pass more readily under the coal and effect a lifting of the overlying mass.

The pan 57 is secured to the frame 2 below the flights 55, and said flights are adapt-

ed to travel along the said pan and convey the coal which is dislodged on to said pan by the action of the diggers or cutters 55. The rear end of the pan is cut away as at 58, to permit the coal to be discharged into the pit wagon 59, which is located in a proper position to receive the coal discharged from said pan.

The sprocket wheel 52 is power driven, being connected up to the motor 35 in the following manner: A beveled wheel 60 on said sprocket wheel is engaged by the beveled pinion 61 on the shaft 26, which as hereinbefore described is connected up by gearing with the motor shaft.

At the forward end of the frame 2 is a skid 62, which is hinged to said frame at 63, so that when said skid is not in use it may be thrown up into position indicated in dotted lines in Fig. 7. This skid is employed in dragging the primary cutting unit off or on to the frame 2.

Connected to the frame 2 is the bracket 64, to which the dog 65 is pivoted. This dog is provided with the teeth 66, and its purpose is to raise the front end of the frame 2 when the machine meets an obstruction in the floor of the mine, so as to prevent the jar on the machine and the breaking of any of the parts, as will more fully hereinafter appear.

To provide for the drilling of holes in the seam of coal for the introduction of an explosive or other substance to expand the coal along its lines of cleavage, the drills 70 are employed. These drills are connected up to a flexible shaft 71 which in turn is connected up to the shaft 72 arranged in bearings 73 at the side of the frame 2. Where shafts 72 are arranged at both sides of the machine they are driven by a system of sheaves. The main sheave 74 is driven by the shaft 29 connected by suitable gearing with the motor shaft. A belt passes around said sheave and around the sheaves 76 and 77 to drive the shafts 72, so that drilling may be done at the same time by both drills.

In carrying out my improved method of mining coal with the above described apparatus, the primary cutting unit is dragged off the frame 2 by its power, the jacks or anchor being properly set to effect this desired result, and an undercut is made in the wall of the coal. The primary cutting unit is indicated in Fig. 1 as making this cut across the wall of the coal, and when the cut has been made, the wall of coal will have the appearance shown in Fig. 4 with the undercut 67. The feed rope 40 is then connected up to the hook 46 on the frame 2, and the primary cutting unit drags itself, under its own power up over the skid 62, and up on to the frame 2, as indicated in Fig. 3. In some seams of coal the coal is

not cut along the floor but the cut is made elsewhere in the seam such as at the top or side, and the coal is loosened from its bed by explosives and expanded into the space made by the cut wherever it may be. It will be noted that the primary cutting unit lends itself to any plan of cutting, either horizontally or vertical, as it is small and flexible with power to move and cut in any direction the rope end is anchored. The shot holes 68 are then drilled in the face of the coal by the drills, one at approximately the middle point and one at each upper corner extending upwardly at an angle. After these shot holes have been drilled the proper charge of powder or other explosives is introduced and the coal is blasted first in the middle and then shots in the corners follow one after the other. The effect of this shooting or blasting will be to cause the coal to expand and become disrupted along lines of its cleavage, as indicated in Figs. 3 and 5, and the lower coal expanded and disrupted from the center shot will settle down on to the floor formed by the undercut 67. The upper coal when shot will expand into the space made by the settling of the lower coal, the front coal falling in loose lumps on the floor, leaving their native bed as indicated in Figs. 3 and 5. It is at this point of the operation that the complete digging, lifting and conveying apparatus is brought into play, and power to operate the same is obtained from the motor of the primary cutting unit, the shaft is connected up with the mechanism for operating the digging, lifting and conveying apparatus, as fully hereinbefore set forth. The lever 19 is moved to drive the traction wheels 5, and the digging and conveying apparatus is brought up into proper position when the chain 54, being driven by the connections described, causes the scrapers or cutters 56 to cut under or undermine the body of coal which has been expanded and disrupted, forming a second undercut, and by this action dislodging the disrupted coal, so that it will drop onto the pan 57 and be conveyed by the flights 55 along said pan until discharged into the mine car 59. By having the frame 2 set at an incline in the manner indicated, it will be noticed that the conveyer flights and the cutters as they advance into the mass of coal, not only cut and dislodge, but wedge upwardly, so with a lifting force under the overlying mass as to assist the dislodgment of the coal by further disrupting it along lines of its cleavage. This feature, however, is not strictly essential, and the same effect may be obtained by advancing the machine on a plane parallel or substantially parallel with the floor of the mine. In case the cutters should strike an obstruction in the floor and it is desired to raise the machine slightly so as to clear

such obstruction, the dog 65 is thrown over to the position indicated by dotted lines in Figs. 3 and 7, and the machine slightly backed up, whereby, by advancing the machine, the dog will bite into the floor of the mine and act to lift the front end of the machine until the obstruction is passed, whereupon the machine is again lowered and the operation continued as before.

In some seams of coal where conditions warrant or require, the wall of coal may be cut horizontally and sheared at the end or middle also, in order to provide more space for the coal to expand in its native bed. After it has been expanded, (and I do not limit myself to explosives in this operation), then the undermining and digging along the floor in the bottom coal will proceed until the coal is undermined and dug from below and removed from its native bed. Projecting points on the upper face of the flights may be so made, (such as projecting bolts shown) as to assist in the digging, and when taken in conjunction with the cutting and scraping points on the end of the flight and an edge on the front edge of the flight, it is obvious that the undermining and digging is effective.

What I claim is:

1. The method of mining coal consisting in undercutting the solid wall of coal, expanding and disrupting the coal along lines of its cleavage, whereby it dislodges and settles down into the undercut, subsequently undercutting this settled mass of coal and simultaneously lifting it with a vertical force traveling laterally in the plane of the first cut to further disrupt the mass along the lines of its cleavage, and simultaneously therewith dislodging the mass of the disrupted coal and conveying it away.

2. The method of mining coal consisting in undercutting the solid wall of coal, expanding the coal and disrupting it along lines of its cleavage, whereby it settles down in the undercut, subsequently undercutting this mass of coal and lifting the settled mass with a vertical force traveling laterally in the plane of the undercut, and simultaneously therewith dislodging the mass of coal and conveying it away.

3. The method of mining coal consisting in undercutting the solid mass of coal, expanding and disrupting the coal along lines of its cleavage, whereby it settles down into the undercut, subsequently undercutting this mass of settled coal along the floor of the original undercut and simultaneously therewith dislodging the mass of settled coal and conveying it away.

4. The method of mining coal consisting in undercutting the solid mass of coal, expanding and disrupting the coal along lines of its cleavage, whereby it settles down into the undercut, subsequently undermining this

settled mass of coal with a force traveling laterally along the floor of the original undercut and simultaneously therewith dislodging the mass of settled coal and conveying it away.

5. The method of mining coal consisting in making a cut in a wall or seam of coal, introducing an expanding force into the body of the coal, thereby expanding and dislodging the coal along lines of its cleavage and into the space made by the cut, making a second cut into the dislodged coal, and simultaneously therewith introducing into said second cut dislodging and conveying forces working in the same plane as said second cut, whereby the coal is dislodged and conveyed away.

6. The method of mining coal consisting of making a cut in the wall of coal, expanding and loosening the solid coal along lines of its cleavage, subsequently making an opening under the mass of loosened coal and in this opening applying a force traveling laterally, whereby the coal mass is moved and further loosened and simultaneously therewith dislodging the mass of disrupted coal and conveying it away.

7. The method of mining coal, consisting of making an opening in a solid wall of coal,

introducing an expanding and disrupting force in the mass of solid coal thereby expanding and loosening the solid coal along lines of its cleavage, subsequently making an opening under the expanded and loosened mass of coal and in this opening introducing a continuous traveling force to distort the mass of loosened coal and simultaneously therewith dislodging the coal and moving it away.

8. The method of mining coal, consisting of making an opening in a solid seam or wall of coal, introducing an expanding force into said seam or wall of coal whereby the solid mass of coal is moved into the opening and loosened along lines of its cleavage, subsequently making an opening in the mass of loosened coal and in this latter opening applying forces to further move the loosened mass of coal and simultaneously therewith dislodging the coal from the loosened mass and moving it laterally.

In testimony whereof, I the said HARRY A. KUHN have hereunto set my hand.

HARRY A. KUHN.
